UNITED STATES PATENT OFFICE

163,129

BUCK SAW

Hubert Lussier, Quebec, Quebec, Canada

Application July 7, 1950, Serial No. 11,003

Term of patent 14 years

(Cl. D93—3)

To all whom it may concern:

Be it known that I, Hubert Lussier, a Canadian citizen, residing at 339 Dorchester Street, city of Quebec, Province of Quebec, Canada, have invented a new, original, and ornamental Design for a Buck Saw, of which the following is a specification, reference being had to the accompanying drawing, forming part thereof.

The figure is a perspective view of a buck saw, showing my new design.

I claim:
The ornamental design for a buck saw, as shown.
HUBERT LUSSIER.
